UNITED STATES PATENT OFFICE.

BARRETT A. FOUST, OF MEADVILLE, PENNSYLVANIA.

HOISTING DEVICE.

No. 905,864.

Specification of Letters Patent.

Patented Dec. 8, 1908.

Application filed February 28, 1908. Serial No. 418,321.

To all whom it may concern:

Be it known that I, BARRETT A. FOUST, a citizen of the United States, residing at Meadville, in the county of Crawford and State of Pennsylvania, have invented a new and useful Hoisting Device, of which the following is a specification.

This invention relates to hoisting devices and more particularly to tackle blocks of that character designed for use in connection with shock loaders and similar devices utilizing hoisting ropes which are suspended from carriages designed to convey hoisted bodies to points of delivery. Heretofore considerable trouble has been experienced in holding the shocks or other bodies being conveyed, in raised positions prior to their discharge onto the rack or other receptacle provided for them.

The object of the present invention is to provide a tackle block having simple means for automatically engaging the hoisting rope so as to lock it and prevent the hoisted material from lowering.

Another object is to provide simple means for releasing the rope.

A still further object is to provide a rope gripping device which is simple, durable and efficient and which will automatically adapt itself to ropes of different sizes and extending at different angles to the horizontal.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a side elevation of the device, the same being shown by dotted lines in locking position. Fig. 2 is a plan view of the parts shown in Fig. 1. Fig. 3 is a perspective view of the gripping shoe and its parts. Fig. 4 is a similar view of a portion of the tripping lever.

Referring to the figures by characters of reference, A designates the body of the block, the same consisting of side plates 1—1 connected at their upper ends by means of a cross bar 2 designed to be engaged by a supporting hook 3 or any other suitable means. From these plates extends a guide yoke 4 integral therewith and extending across the periphery of a sheave 5 journaled between the plates. Studs 6 extend from the plates

at points diametrically opposite the yoke 4 and fulcrumed upon these studs is a yoke-like tripping lever 7 which embraces the block A and has one of its arms elongated 60 as indicated at 9 and provided with a laterally extending finger 10 to which the tripping rope or cord 11 is secured.

Extending through the crown portion of the lever 7 is a pivot bolt 12 upon the end 65 portions of which are pivotally mounted links 13. The ends of these links are seated loosely within grooves 14 formed in the ends of a gripping shoe 15, said shoe being preferably formed of a metal plate having its 70 end portion bent at right angles as indicated at 16 and provided with the grooves 14 herefore referred to. The side walls of these grooves preferably converge and constitute stops for limiting the movement of the shoe 75 15 relative to the links 13. The working face of the shoe 15 is preferably formed with diagonally disposed grooves 17 designed to constitute seats for portions of the hoisting rope clamped by the shoe. The 80 shoe 15 is connected to the links 13 by means of a pivot bolt 18 which extends through the links and through the ends 16.

Formed upon the side plates 1 between the guide yoke 4 and the cross bar 2 are 85 laterally extending spacing flanges 19 which serve to hold links 13 out of contact with the pulley block so that friction is thus reduced to the minimum. They also serve, in connection with the pivot bolt 12, to hold the 90 links 13 so positioned as to prevent lateral displacement of the gripping shoe 15 relative to the flanges 19.

Formed within the lower portion of the tackle block A is a cross bar 20 to which is 95 bolted or otherwise secured a spacing block 21 having a shield or guard plate 22 secured thereto. This plate is preferably curved upwardly toward its ends from its points of connection with block 21 and that portion of 100 the plate below the studs 6 has an elongated slot 23 therein the edge portions of which are preferably provided with downwardly extending guide flanges 24. An angular opening 25 is preferably formed in that end 105 of the plate 22 located below the guide yoke 4 and guide flanges 26 are preferably struck downward from the plate so as to constitute guards along the edges of this opening 25.

A stop lug 27 is formed upon one of the 110 plates 1 and holds the brake shoe in position to ride upon the rope. It also holds the

weighted portion of lever 7 at such an angle as to balance finger 10 and trip rope 11 into set position.

The hoisting rope, which has been indicated at B, extends over the sheave 5 and through the yoke 4 and the yoke portion of lever 7. That end portion of this rope to which power is applied extends through the opening 23 while the other end portion is designed to normally rest within the opening 25. The normal position of the shoe 15 is upon the yoke 4 as indicated by full lines in Fig. 1. When a shock of corn or other material is to be hoisted the free end of the rope B is extended at an angle from the block as indicated in Fig. 1 and fastened to the shock, after which power is applied to the rope and the same is pulled in the direction of the arrow in Fig. 1. Inasmuch as the shoe 15 is in contact with the rope B it will be carried upward therewith and cause the links 13 to push against the yoke portion of lever 7 and when the bolt 12 and stud 6 are brought into line with the longitudinal centers of the links 13 the crown portion of lever 7 will swing downward and cause arm 9 to swing upward until its finger 10 contacts with one of the links 13. The parts will then be positioned as indicated by dotted lines in Fig. 1. There will still be sufficient space between the gripping shoe 15 and the sheave to permit the rope B to continue its movement in the direction of the arrow until the shock has been raised to a desired elevation. When, however, the power is removed from the rope the weight of the shock will pull the rope for a short distance in the opposite direction. As the gripping shoe 15 is in contact with the rope it will press thereinto and be drawn downward therewith and held by yoke 4. The gripping action of this shoe upon the rope will increase in proportion to the weight to which the rope is subjected and it will be obvious therefore that downward movement of the shock will be absolutely prevented as long as the parts are positioned as indicated by dotted lines. While the shock is thus held supported the tackle block can be conveyed by means of a supporting carriage, not shown, to any desired point and the shock can then be lowered simply by pulling downward on rope 11. This will cause lever 7 to swing upon its bearings 6 and push the bolt 12 upward above said bearings whereupon the gripping shoe will be released from frictional engagement with the rope B and said rope will be free to move downward so as to lower the shock. By maintaining perpendicular that end portion of the rope to which the shock is to be attached the rope can be raised or lowered without interference by the gripping shoe but by extending the rope from the block at an angle as indicated in Fig. 1 the grip-

ping shoe will be caused to assume a set position as heretofore stated so as to automatically engage and hold the rope to prevent return movement. The gripping shoe 15 is pivotally connected to the links 13 so that it has a limited locking movement relative thereto whereby it can automatically adjust itself to the rope. The guard or shield is useful inasmuch as it prevents portions of the shock from coming into contact with the working parts of the block.

Although the device has been described as particularly designed for hoisting shocks and the like and conveying them to points of discharge it is to be understood that the same can also be used for any other purpose where it is desired to raise one or more objects and maintain them in raised position until it is desired to lower them.

What is claimed is:

1. The combination with a tackle block, a guide yoke extending therebeyond; of a tripping lever fulcrumed upon the block, a gripping shoe normally supported upon the yoke, and link connections between the tripping lever and the shoe, said lever being foldable upon the links when the shoe is shifted in one direction to hold the shoe in gripping position.

2. The combination with a tackle block having a rope supporting sheave therein; of a tripping lever fulcrumed upon the block, a gripping shoe disposed to frictionally engage and to be shifted in one direction by the rope, and link connections between the shoe and lever, said connections being disposed to fold the lever against the links to lock the shoe in gripping position when the rope is moved in the opposite direction.

3. The combination with a tackle block having a rope supporting sheave therein, and a guide yoke extending from the block; of a tripping lever fulcrumed upon the block, a gripping shoe normally resting upon the yoke and disposed to frictionally engage and to be shifted by the rope when moved in one direction, and link connections between the shoe and tripping lever for transmitting motion from the shoe to the lever to fold said lever upon one of the links during said movement of the gripping shoe.

4. The combination with a tackle block having a rope supporting sheave therein, and a guide yoke extending from the block; of a tripping lever fulcrumed upon the block, a gripping shoe normally resting upon the yoke and disposed to be shifted in one direction by the yoke, a pivoted connection between the shoe and lever for transmitting motion from said shoe to the lever to fold said lever upon the connection and lock the shoe in frictional engagement with the rope.

5. The combination with a tackle block having a rope supporting sheave therein; of a tripping lever fulcrumed upon the block,

a gripping shoe disposed to be shifted into set position by the rope, a pivoted connection between the shoe and lever for folding said lever upon the connection to lock the

5 shoe in set position.

6. The combination with a tackle block having a rope supporting sheave therein, and a guide yoke extending from the block; of a tripping lever fulcrumed upon the 10 block, a gripping shoe normally mounted thereon and disposed to be shifted into set position by the movement of the rope in one direction, means for transmitting motion from the shoe to the tripping lever to fold 15 said lever against said means during said movement of the shoe, said shoe when set being positioned to bind upon the rope and prevent its movement in one direction.

7. The combination with a tackle block 20 having a rope supporting sheave therein, and a guide yoke extending from the block; of a combined rope guide and tripping lever fulcrumed upon the block, a gripping shoe disposed to be shifted in set position by the 25 rope when moved in one direction, and means for transmitting motion from the shoe to the tripping lever during said movement to fold the lever upon said means, said shoe when in set position being disposed to 30 prevent movement of the rope in one direction.

8. The combination with a tackle block having a rope supporting sheave therein and a guide yoke extending from the block; of a 35 combined rope guide and tripping lever fulcrumed upon the block, a gripping shoe normally supported upon the yoke, a link connection between said shoe and the tripping lever, said shoe being movable by the rope in 40 arcs eccentric to the sheave and said link connection and lever co-operating to lock the shoe in gripping position.

9. The combination with a tackle block having a rope supporting sheave therein, 45 and a guide yoke extending from the block; of a combined rope guide and tripping lever fulcrumed upon the block, a gripping shoe normally resting upon the yoke and disposed to be shifted into set position thereby, a link 50 connection between the shoe and tripping lever for transmitting motion to said lever

from the shoe to fold the lever upon said connection when the shoe is in set position, and means for shifting the tripping lever out of folded position.

55

10. The combination with a tackle block having a rope supporting sheave thereon and a guide yoke extending from the block; of a combined rope guide and tripping lever fulcrumed upon the block, links pivotally 60 connected thereto, a gripping shoe connected to and mounted to rock between the links and normally resting upon the yoke, said shoe being shiftable into set position by the rope to fold the lever upon one of the links. 65

11. The combination with a tackle block having a rope supporting sheave thereon and a guide yoke extending from the block; of a combined rope guide and tripping lever fulcrumed upon the block, links pivotally 70 connected thereto, a gripping shoe connected to and mounted to rock between the links and normally resting upon the yoke, said shoe being shiftable into set position by the rope to fold the lever upon one of the links, 75 laterally extending spacing flanges upon the block and constituting bearings for the links, and means for shifting the tripping lever out of folded position.

12. The combination with a tackle block 80 having a rope supporting sheave and a guide yoke extending from the block; of a guard plate connected to and extending under the block, said plate having rope receiving openings therein, a gripping shoe normally 85 mounted upon the yoke, a tripping lever fulcrumed upon the block, link connections between the shoe and tripping lever, said shoe being shiftable into set position by the rope to fold the tripping lever upon one of 90 the links, said shoe when set being movable in a plane eccentric with the sheave, and means for shifting the tripping lever out of folded position to shift the shoe out of set position. 95

In testimony that I claim the foregoing as my own, I have hereto affixed my signature in the presence of two witnesses.
